Primary Examiner—Bernard Ansher

Assistant Examiner—Theodore M. Shooman

Attorney, Agent, or Firm—Sughrue, Mion, Zinn,
Macpeak & Seas

[73] Assignee: NEC Corporation, Tokyo, Japan

[57] CLAIM

The ornmental design for a transmitter and receiver for
microwave communications, as shown.

[**] Term: 14 Years

DESCRIPTION

[21] Appl. No.: 278,310

FIG. 1 is a right side elevational view of a transmitter
and receiver for microwave communications showing
our new design;

[22] Filed: Nov. 30, 1988

FIG. 2 is a top plan view thereof;

[30] Foreign Application Priority Data

FIG. 3 is a left side elevational view thereof;

May 30, 1988 [JP] Japan 63-21467

FIG. 4 is a front elevational view thereof;

[52] U.S. Cl. D14/231; D14/230

FIG. 5 is a rear elevational view thereof;

[58] Field of Search D14/230-238;

FIG. 6 is a bottom plan view thereof; and

343/720, 721, 730, 741, 746, 747, 748, 805, 806,
815, 820, 872, 873, 907, 908, 909

FIG. 7 is a rear, top and right side perspective view
thereof.
